(57) **CLAIM**

The ornamental design for a taco and flatbread shell forming instrument, as shown and described.

DESCRIPTION

FIG. 1 is a perspective view of a taco and flatbread shell forming instrument;

FIG. 2 is a front elevation view of the taco and flatbread shell forming instrument;

FIG. 3 is a rear elevation view of the taco and flatbread shell forming instrument;

FIG. 4 is a left-side elevation view of the taco and flatbread shell forming instrument;

FIG. 5 is a right-side elevation view of the taco and flatbread shell forming instrument;

FIG. 6 is a top plan view of the taco and flatbread shell forming instrument; and,

FIG. 7 is a bottom plan view of the taco and flatbread shell forming instrument.

1 Claim, 7 Drawing Sheets
